UNITED STATES PATENT OFFICE.

JOHN P. WEIS, OF BROOKLYN, NEW YORK, ASSIGNOR, BY MESNE ASSIGNMENTS, TO METROPOLITAN SEWING MACHINE COMPANY, A CORPORATION OF NEW YORK.

SEWING AND TRIMMING MACHINE.

1,081,797.

Specification of Letters Patent. Patented Dec. 16, 1913.

Application filed April 23, 1903. Serial No. 153,908.

To all whom it may concern:

Be it known that I, JOHN P. WEIS, a citizen of the United States, residing in Brooklyn, county of Kings, and State of New York, have invented a new and useful Improvement in Sewing and Trimming Machines, of which the following is a description.

This invention relates to machines for sewing and trimming fabrics, and particularly to a mechanism by which the sewing and trimming can be done simultaneously, and by which the trimming mechanism can be thrown into and out of operation during the sewing without affecting the stitching operation and without affecting the running of the machine.

An object of my invention is to provide means whereby the work may be sewed and trimmed and have a tape secured thereto simultaneously.

Another object of my invention is to provide means whereby a tape may be secured to the work under tension, and the work fulled or puckered, or stretched on the tape to the extent desired. And another object of my invention is to provide means whereby the trimmer, connected to some moving part of the machine, may be thrown into and out of action without affecting the stitching or such moving part. And still another object is to provide means whereby simultaneously with the adjustment of the feed for the purpose of fulling the work, tension may be applied to the tape which is being secured thereto.

With the above objects in view, and others which will be hereinafter noted, the invention consists in the mechanism, elements, features and combinations hereafter described and claimed.

In the drawings: Figure 1 is a perspective view showing a portion of a sewing machine and particularly illustrating the feed mechanism and the tension for the tape, together with the means whereby both the tension and the feed are operated from a common means; Fig. 2 is a plan view of a portion of the machine and illustrating the trimmer mechanism and the relation of the latter to the stitching position; Fig. 3 is a side elevation of the mechanism shown in Fig. 2, the driving shaft, cloth-plate and bed-plate being shown in section; Fig. 4 is a vertical sectional view on the line 4-4 of

Fig. 2; Fig. 5 is a front elevation of the mechanism shown in Fig. 2, showing the cloth-plate and bed-plate in section, and showing the driving shaft broken away so as to illustrate the bracket for supporting the trimming mechanism; Fig. 6 is a front elevation of so much of a sewing machine as is deemed necessary to illustrate my invention in connection with a stitch-forming mechanism, including a needle and looper; and Fig. 7 is a partial section and end elevation of the parts shown in Fig. 6 and illustrating the manner in which the looper, needle, feed, trimmer and presser-foot are arranged and coöperate in accordance with my invention.

Primarily, it should be understood that this machine is constructed for the purpose of attaching a tape to certain portions of the body of a coat or like garment; that is to say, men's coats are ordinarily provided with a stiffening in the breast portions thereof, and to prevent the coat from sagging or wrinkling, and to preserve the curvature thereof along the front edge, it is necessary to apply a tape of heavy woven material to the stiffening so as to support the weight of the coat. And, in order to properly impart the requisite curvature and maintain the proper relation of the stiffening and coat-material, it is necessary to attach the tape under tension, or to "full" or to stretch the material of the coat upon the tape and stiffening. Heretofore this operation has been done entirely by hand and has proven a tedious, lengthy and laborious operation. And certain portions of the garment, around its edges, have to be trimmed while other portions do not have to be trimmed; and, heretofore, it has been necessary, in passing from the portion to be trimmed to the portion not to be trimmed, to stop the machine and throw the cutter out of operation. Obviously, this is a great waste of time and involves a great expense.

By the mechanism illustrated and now to be described the several desirable objects are fully secured and the operation and functions are accurately and perfectly performed.

1, is the bed-plate; 2, the cloth-plate; 3, the driving shaft, journaled in the bed-plate and carrying at its forward end, as is usual, any suitable means for actuating the feed mechanism to impart its feeding movement,

through the medium of the connection 4, to the rocking frame 5. Said shaft also carries the eccentric 6, engaged by the bracket 7, on the feed-bar 8, as usual, for giving the rise and fall to the feed-bar. The feed-bar carries the feed-dog 9, vertically adjustable thereon by means of a screw 10, as is usual. The feed-bar, in rear of the dog 9, is provided with a vertically extending lug 10^a, to which is pivoted the lever 11, having at its rear end the sleeve 12, surrounding the shaft 13, journaled in bearings 14, to the rocking frame 5, which in turn is journaled to the bed-plate through the medium of a shaft 15, to which the frame is fixed by means of the screws 16. In rear of its journal the lever 11, is provided with the extension 17, through which freely extends a screw 18, and which screw threads into an extension 19, at the rear end of the feed-bar 8. This connection, between the rear ends of the lever and feed-bar, is for the purpose of adjusting the feed-bar thus regulating the bearing of the feed-dog upon the work; that is to say, by depressing the rear end of the feed-bar the same will be caused to pivot at 10^a upon the lever 11, and throw the heel of the dog from contact with the work and the toe of the dog into contact with the work, thus causing the feed to be in advance of the stitching position and the work to be fed up to the stitching position and fulled or slightly puckered, for a purpose hereinafter described. In order to properly brace the parts and cause the lever 11, and feed-bar 8, to maintain their relation laterally, a lug or lugs 20, may be provided on the bar 8, to engage and guide the lever 11. A jam-nut 21, may be placed upon the screw 18, between the extensions 17, and 19 to maintain the desired adjustment. The presser-foot 22 is provided at its forward end with an enlarged portion at opposite sides, indicated by 23, in which is supported a spindle 24. A guide 25 is slidably supported on the spindle and is held in adjusted position thereon by means of a screw α . The guide, see Figs. 1, 6 and 7, is in the form substantially of a bell-crank lever, the fulcrum of which, at the angle, is the spindle 24. The screw α passes through the horizontal arm, which overhangs the presser-foot, and the vertical arm depends into engagement with the front part of the foot, Fig. 6. Being screw-threaded into the said horizontal arm of the gage and impinging upon the top surface of the presser-foot, see Figs. 1 and 7, by turning the screw in one direction, the depending arm of the gage will bind tightly against the toe of the presser-foot and will thus be held in fixed position. To adjust the gage, the screw is turned in the opposite direction, thereupon releasing the gage from engagement with the foot and permitting

said gage to be moved along the spindle 24. This is a common construction and further details are considered to be unnecessary.

Suitably held upon the shaft 13, close beside the lever 11, is a cam-lever 26, the same having a depending cam portion 27, for engaging the feed-bar 8, whereby the same may be raised and lowered relatively to the lever 11, by means of a chain 28, or other suitable means, connected to the rear end of said lever 26, operated in any suitable manner from below the bed-plate. A spring 29, surrounds the shaft 15, and has an end 30, extending vertically into contact with the cam end of the lever 26, so as to keep said end normally depressed and give the same a tendency to return to its normal position shown in Fig. 1. A collar 31, is fixed upon the shaft 15, by means of a screw 32, and the spring 29, has one end connected to said collar and through the medium of the latter tension of the same may be regulated by turning the collar upon the shaft by means of an instrument inserted in an aperture 33, one or more of which may be provided for the purpose in the collar.

Secured to the bed-plate by means of the screw 34, is a bracket 35, to which is pivoted a lever 36, by means of the screw 37, which lever, at one end, is provided with a spring extension 38, entering a slot 39, in the rear end of the lever 26. The other end of the lever 36, is extended to engage a cam 40, carried on the lower end of a lever 41, pivoted at 42, to a vertical rod 43, suitably secured in the bed-plate as shown in Fig. 1. The upper end of the lever 41, is grooved or curved at 44, to conform to the circumference of the rod 43, and just below its upper end said lever is provided with a hub 45, into which is tapped a set-screw 46, for the purpose of engaging the rod 43, and regulating the pressure of the lever 41, upon the tape which passes between the same and the rod 43. Normally, the spring 47, secured to the rod 43, by means of a screw 48, and bearing upon the lever 41, below its pivot 42, keeps the end 44, of said lever away from the rod 43, thus allowing the tape to pass free of tension. A tape-guide 49, of any suitable character is secured to the rod adjacent the upper end of the lever 41.

From the above description it will be clear that the feed may be caused to bear upon the work either in front of or behind the stitching position, and may also be caused to operate throughout its length upon the work as usual, this depending entirely upon the adjustment of the feed-bar relatively to the lever 11. It will also be clear that when the lever 26, is depressed, by manipulating the chain 28, the forward end of the dog, in advance of the stitching position, will be caused to engage the work and feed the same up to said stitching position.

When this function is accomplished the spring end of the lever 36, is likewise depressed, thus causing its other end to engage the cam 40, on the lever 41, which will cause the upper end 44, of said lever to move toward the rod and apply tension to the tape. The object of this manipulation is to cause the tape to pass the stitching point under tension, and to cause the work, or body fabric, to be fulled upon the tape as previously stated. By providing the spring end 38, on lever 36, great and extreme adjustments of the feed may be made without applying excessive tension to the tape; and after the set-screw 46, has been set so as to regulate the tension on the tape, an extreme depression of the spring end 38, will not affect the said tension, and said end will readily yield to accommodate the depression of the lever 26. These are important functions in my machine.

In the claims I have referred to the regulation of the feed stroke of the feeding member, to means for regulating the action of the feed, and means for adjusting the bearing of the feed device upon the work, and in various other ways have endeavored to cover the several modes of operation of my feeding mechanism, in combination with the other features and elements of my machine; and in so doing, I desire it understood that I intend to cover, by the language employed, not only the idea of means of regulating the effective feed stroke of the feed member upon the work, but the effective feed movement of the feed member during its operation. The terms which I have employed to express my regulating and adjusting means are intended to be generic with a view to avoiding restriction to such adjustments as are common and usual in sewing machines in connection with the feed mechanism thereof.

In operating upon the class of goods before mentioned it is desirable to trim at certain points and along certain lines and, at other times and in other places in the work, to throw the trimmer out of operation; and this must be done, to secure good results and rapid operation of the machine, without stopping the latter, the stitching, or affecting the latter in any way. This is accomplished as follows: Secured to the bed-plate 1, is an angular bracket 50, by means of a screw 51, the same affording a journal bearing for the shaft 52, which at its forward end has secured thereto an arm 53, having connected thereto a link 54, the upper end of which is connected to the rear end of a lever 55, carrying a pin 56, journaled in a bearing 57, formed on or connected to an eccentric strap 58, surrounding an eccentric 59, carried near the forward end of the shaft 3. The rear end of the eccentric strap 58, carries a pin or bolt 60, swivel-

ing therein, said bolt being suitably connected to a shaft 61, passing through bearing 62, to the front of the machine at which point said shaft 61, supports a looper carrier 61^a having a looper 61^b, as is usual. Said looper has its longitudinal movements imparted by the rod 61^b driven as usual.

It may be observed at this point that the eccentric, eccentric-strap and shaft 61, are parts of the usual looper mechanism by which the looper is given its lateral vibration, or needle avoiding movement; and this looper mechanism constitutes the constantly moving part of the machine, when in operation, to which the trimmer has been connected for the purposes stated. The forward end of the eccentric strap is enlarged and provided with an angular socket 63, for the reception of a holder 64, for the trimmer-blade 65, the holder being made angular as shown in Fig. 5, and the vertical portion 66, being retained in the socket 63, by means of a clamping-screw 67, passing through the two parts of the forward end of the eccentric-strap which is provided with a saw-cut 68, for the purpose, this construction making a clamp for retaining the trimmer-holder from lateral movement, but permitting it to have vertical movements. The trimmer-holder is also provided with a saw-cut 69, providing a clamp between the parts of which the blade 65, is held by means of a clamping screw 70, the socket of the clamp being dove-tailed and the blade being correspondingly formed. At one side the wall 100 of the socket 63, is provided with an elongated slot 71, through which extends a screw 72, secured to the holder 64; and the forward end of the lever 55, is provided with an elongated slot 73, for engaging the screw 72. 105 From this construction it will be seen that while the eccentric-strap 58, is constantly operating or moving during the operation of the machine, thus imparting motion to the trimmer-holder and blade, still, by manipulating the lever 55, and depressing the forward end thereof, the trimmer-blade may be depressed below the cloth-plate and out of operative position. The position of the lever 55, determining the position of the blade 110 65. To manipulate the lever 55, the shaft 52 is provided at its opposite end with a depending arm 74, to the lower end of which is connected the bar 75, provided with the manipulating ring or handle 76; and to hold the bar 75, in either of its extreme positions, i. e., to hold the trimmer-blade in action or out of action, the bed-plate 1, is provided with a vertical post 77, which co-operates with the notches 78 and 79, in the bar 75. 115 120 From this construction it will be seen that when the bar 75, is in its extreme forward position shown in Fig. 3, and the post 77, is seated in the notch 79, the trimmer blade is rigidly held in operative position, and by the 125 130

rotation of the eccentric and the actuation of the strap 58 thereby, the trimmer-blade will be caused to trim the work simultaneously with the stitching. When, however, 5 the bar 75, is thrown to the opposite extreme,—as by lifting the same and bringing the notch 78, into coöperation with the post 77,—the trimmer-holder will be depressed in the socket 63, of the eccentric-strap 58, 10 and will be thrown out of operation, and this without affecting the operation of the machine or modifying the action in any particular of any of the usual operating parts thereof.

15 The trimmer-blade is formed as usual with the beveled portion 80, and the finger 81, which guides the blade into proper co-operative and actuating relation with a portion 82, of the presser-foot 22, see Fig. 2, 20 which foot is connected in any suitable manner to the presser-bar 83, guided in the head of the machine as usual.

In order to properly guide the tape to the stitching point, a guide 84, is carried by 25 a post 85, on the head of the machine, said guide having a loop 86, at each end for guiding the tape to the stitching point after passing from the guide 49. The tape to be applied to the garment, as herein described, is 30 led from the reel or supply to the stitching position by being first passed through the guide 49 and then between the rod 43 and the upper end 44 of the tension lever. From thence the tape is passed through the loop 35 86 and then through the loop 86'; between which points said tape is given a half turn, as clearly shown in Fig. 1, this being for the purpose of guiding the tape smoothly through the loop 86'. From the latter loop 40 the tape is led to and under the spindle 24 of the presser-foot and between the adjacent guide and one side of said foot, the tape passing under the presser-foot as shown by the dotted lines in Fig. 1. Thus, the tape is 45 controlled and subjected to tension during its entire course of travel from its supporting reel to the point of application to the work.

From the above description a detailed 50 statement of the operation of the machine will not be necessary, it being obvious that if the trimming and sewing are to be begun simultaneously, the trimming mechanism will be thrown into the position of Fig. 3; 55 and that when the point in the work has been reached where trimming is no longer necessary, the bar 75, will be lifted, quickly thrown backwardly and then depressed so that the post will coöperate with the notch 60 78, and the trimmer will be instantly thrown out of action without interfering with the stitching operation. Furthermore, it will be obvious that when the tape is being laid in under tension the feed will be manipulated 65 so that its action will be entirely in front of

the stitching position and the material of the garment will be fulled upon the tape, which latter will be, in consequence, stretched relatively to said material. Furthermore, when the tape has been laid to the desired extent it may be quickly grasped by the hand of the operator and, if the trimming blade is in operation, may be turned across said blade and cut off, thus avoiding the necessity for the operator to pick up a pair of scissors and cut the tape. Ordinarily, the fulling of the material, the application of the tape and the trimming of the material proceed simultaneously; hence, when it is desired to cut the tape the trimmer is in action and may be continued in action or instantly thereafter may be thrown out of action.

Having thus described my invention what I claim and desire to secure by Letters Patent is:

1. In combination, stitch-forming mechanism including a looper and its actuating mechanism; a trimmer-blade; a trimmer-blade holder carried by a part of the looper-actuating mechanism and freely movable relatively thereto; and means for actuating said blade-holder relatively to said looper-actuating part for depriving said trimmer-blade of its cutting function at will.

2. In a sewing machine, and in combination with the stitch-forming mechanism thereof; a trimmer-blade; a holder for said trimmer-blade mounted below the cloth-plate of the machine on a part of the stitch-forming mechanism and freely movable relatively thereto; and means for actuating said holder relatively to said part whereby the trimmer-blade may be deprived of its cutting function at will without affecting the stitch-forming mechanism.

3. In combination; a stitch-forming mechanism including a looper, a driving-shaft and means for actuating the looper; a trimming mechanism supported and actuated by the looper-actuating means; and means for depriving the trimming mechanism of its cutting function during the operation of the machine and without disturbing the action of the stitch-forming mechanism.

4. In combination, a driving-shaft; a stitch-forming mechanism actuated by said shaft and including a looper-mechanism, the looper mechanism comprising a looper-actuating eccentric and strap; a trimming mechanism supported by the strap; and means for throwing the trimming mechanism into and out of operation during the operation of the stitch-forming mechanism.

5. In combination, a driving-shaft; stitch-forming mechanism actuated by said shaft; a trimming mechanism supported and actuated by a portion of the stitch-forming mechanism; and means for operating directly upon the trimming mechanism, for

- throwing it into and out of operation, including a rock-shaft, and an actuating bar.
6. A sewing machine having in combination a stitch-forming mechanism including a driving eccentric and strap; a trimmer-holder carried by the strap; a trimmer-blade carried by the holder in position to operate through the cloth-plate of the machine; and means for throwing the trimmer-blade into and out of operation during the running of the machine.
7. A sewing machine having in combination a stitch-forming mechanism including a driving eccentric and strap; a trimmer-blade supported by the strap; mechanism for moving the trimmer-blade relatively to the strap including means whereby the trimmer-blade may be thrown into and out of operation during the running of the machine.
- 20 8. A sewing machine having in combination a stitch-forming mechanism including a driving eccentric and strap; a trimmer-holder carrying a trimmer-blade; means supporting the holder upon the strap; and means carried by the strap whereby the holder may be moved relatively thereto.
9. A sewing machine having in combination a stitch-forming mechanism including a driving eccentric and strap; a trimmer-holder carrying a trimmer-blade, supported upon the strap; means for sliding the holder upon the strap; and means independent of the stitch-forming mechanism for actuating the means which slides the holder.
- 35 10. In a sewing machine, and in combination with a stitch-forming mechanism, a feeding mechanism having a tilting feeding-device; a trimming mechanism; a tape-guiding mechanism; means for applying tension to the tape; and means for actuating the tilting feeding-device to cause the same to full the work.
11. In a sewing machine, and in combination with a stitch-forming mechanism, a feeding mechanism having a tilting feeding-device; a trimming mechanism; a tape-guiding means; means for applying tension to the tape; and means whereby the tilting feeding-device may be caused to full the work and tension may be simultaneously applied to the tape.
- 50 12. In combination, a stitch-forming mechanism; feeding mechanism; means for regulating the feed stroke of the feed-member of the feeding mechanism; trimming mechanism; and tape-guiding mechanism; means whereby at will the extremes of movement of the feed-member of the feeding mechanism may be obtained; and means whereby, in shifting from one extreme to the other of the movement of the feed-member, tension may be simultaneously applied to the tape.
- 55 13. In combination, a feeding-device; stitch-forming mechanism; trimming mech-
- anism; and a tape-guiding mechanism; means for adjusting the bearing of the feed-device upon the work; and a device connecting the tape-guiding mechanism and the feed-adjusting means whereby when the latter is operated tension will be applied to the tape.
14. In combination, a stitch-forming mechanism; a feeding mechanism; a trimming mechanism; a tape-guiding mechanism; means for applying a certain tension to the tape; means whereby the dog of the feeding mechanism may be caused to full the work to a predetermined degree; and means whereby such degree of feed may be varied without altering the degree of tension.
15. In combination, a stitch-forming mechanism; a feeding mechanism; a trimming mechanism; a tape-guiding mechanism; means for applying a certain degree of tension to the tape and simultaneously therewith regulating the action of the feed to a predetermined extent; and means for changing the action of the feed without altering the degree of tension.
- 25 16. In combination, a stitch-forming mechanism; a feeding mechanism; a trimming mechanism; a tape-guiding mechanism; means for applying a certain degree of tension to the tape; means whereby the feed may be caused to full the work to a predetermined degree; and means whereby the tension may be varied without altering the action of the feed.
- 30 17. A sewing machine comprising stitch-forming mechanism; feeding mechanism; trimming mechanism; tape-guiding mechanism, including a tension-device; common means for regulating the action of the feed and for applying the tension to the tape; said means including a device whereby, when the requisite degree of tension has been applied to the tape, a further adjustment of the feed action will not affect said tension.
- 35 18. A sewing machine comprising stitch-forming mechanism; feeding mechanism; trimming mechanism; and a tape-guiding mechanism whereby, when the action of the feed is altered, tension may be applied to the tape, said means including a yielding connection.
- 40 19. In combination, a stitch-forming mechanism; a feeding-mechanism; a trimming mechanism; means whereby the feeding mechanism may be caused to full and stretch the work at will; and means for throwing the trimming mechanism into and out of operation during the operation of the feeding and stitch-forming mechanisms.
- 45 20. In combination, a stitch-forming mechanism; a feeding mechanism having a

tilting feeding-device; a trimming mechanism; a tape-guiding mechanism; means for applying tension to the tape; and means for actuating the tilting feeding-device to full the work.

21. In combination, a stitch-forming mechanism; a feeding mechanism; a trimming mechanism; a tape-guiding mechanism; means for applying tension to the 10 tape; means for actuating the feed to full the work and simultaneously changing the tension of the tape; and means whereby the trimming mechanism may be thrown into and out of operation during the operation of the machine.

22. In combination, a stitch-forming mechanism; feeding mechanism; trimming mechanism; a tape-guiding mechanism; means whereby the feeding mechanism may

be caused to full the work and simultaneously tension may be applied to the tape.

23. In combination, a stitch-forming mechanism; feeding mechanism; trimming mechanism; tape-guiding mechanism; means whereby the feed may be caused to full the 25 work and simultaneously therewith tension may be applied to the tape; and means whereby the trimming mechanism may be thrown into and out of operation during the operation of the machine.

In testimony whereof, I have hereunto signed my name in the presence of two subscribing witnesses.

JOHN P. WEIS.
